UNITED STATES PATENT OFFICE.

JOSEPH H. POPE, OF HAMILTON, MASSACHUSETTS, ASSIGNOR TO UNITED SHOE MACHINERY COMPANY, OF PATERSON, NEW JERSEY, A CORPORATION OF NEW JERSEY.

HEEL-PRESS.

1,161,883.

Specification of Letters Patent.

Patented Nov. 30, 1915.

Application filed February 3, 1914. Serial No. 816,351.

To all whom it may concern:

Be it known that I, JOSEPH H. POPE, a citizen of the United States, residing at Hamilton, in the county of Essex and State 5 of Massachusetts, have invented certain Improvements in Heel-Presses, of which the following description, in connection with the accompanying drawings, is a specification, like reference characters on the drawings indicating like parts in the several figures.

This invention relates to presses, and especially presses for heels used in the manufacture of shoes.

15 An important object of my invention is to provide a readily manipulated pressure head which can be adjusted quickly to any height of stock to be pressed within the limits of the capacity of the machine and I prefer to 20 utilize a toggle lever as means for securing the pressure head at the desired point. Such a head exerts a very strong distortive action upon the frame of the press and another important object is to provide the 25 pressure head with means to afford a countervailing force so that the machine will not be subject to destructive distortion. I prefer to employ columns or standards as the means for guiding and supporting the 30 pressure head, and in accordance with my invention in its preferred form I supply means for gripping both sides of each of the two upright standards ordinarily employed so that the stresses neutralize each other.

35 Another object of my invention is to provide a clamp in the form of a cam collar, operating a coil spring arranged to exert a gripping action upon each of the columns to which reference has above been made.

40 The various features of my invention will be illustrated and described fully in the accompanying drawings and specification and pointed out in the claims.

In the drawings, Figure 1 is a view in 45 perspective of a heel press in the construction of which my improvements have been embodied; Fig. 2 is a fragmentary view in front elevation of the same, showing the pressure head in operation upon heel stock, parts being broken away to reveal interior 50 construction; Fig. 3 is a view similar to Fig. 2 of a modified form of clamping device; and Fig. 4 is a fragmentary detail view upon an enlarged scale of the coöperating cam devices to operate the clamp.

In the drawings, the part designated by the reference numeral 1 is the base of a heel press, and 2 designates the head of the press, the numeral 3 designating standards, or upright columns, connecting the base and head, 60 secured in place by set screws 4, the standards being cylindrical.

I provide a pressure head comprising a platen 5, having guide sleeves 6, mounted upon the columns 3, and I provide also in 65 suitable form an operating device for the platen such for example, as a toggle lever comprising arms 7, pivoted to jaws 8, and also pivoted at their other ends to a collar 9, threaded to receive an operating screw 70 10 with a hand wheel 11, at its free end, the other end of the screw bearing against a suitable bearing piece 12, mounted upon the platen, with which the screw may, and preferably will, have a ball connection as shown 75 at 13, in Fig. 2.

In order to steady the toggle in its operation, and to afford suitable fulcra for the lever arms 7, I have shown the latter as pivoted at 14 to sleeves 15, mounted upon 80 the uprights 3, above the sleeves 6, the sleeves 15 being apertured as at 16 to give access for the jaws 8, to the uprights 3.

In accordance with an important object of my invention I provide means to furnish 85 a countervailing support for the columns 3 at a point upon their circumference diametrically opposite to that subject to the thrust of the jaws 8, and this may take any suitable form. As one convenient form I 90 have shown a link 17, with turnbuckles 18, provided with jam nuts 19, so that a strong support is provided to prevent distortion of the columns 3.

The parts designated by the reference numerals 20 are counterweights connected with the pressure head by flexible cables 21, passing over pulleys 22, supported in brackets 23, upon the head of the frame, the cables being connected by suitable devices with 100 the pressure head as indicated at 24.

In Figs. 3 and 4 I have shown a modified form of clamping device in which the coiled springs 30 afford a means for gripping the columns 31. One end 32 of each of these 105 springs enters a recess in the sleeve 33, which serves as the toggle fulcrum, having ears 34, for that purpose, while the other end 36 of the spring enters a similar recess in a collar 37, mounted in position to rotate upon 110

the column 31, being preferably retained in position by a finger 38, formed integrally with the sleeve 33. This collar has a cam shoulder 39 to be engaged with a coöperating cam knuckle 40, mounted pivotally at 41 on the toggle arm 47. The arms 47 are connected pivotally at 48 with an operating collar 49 traversed by an operating screw shaft 50, having a hand wheel 51 and connected at 52 with the platen 53, the latter having sleeves 54 as heretofore described to slide upon the columns 31, the latter being supported in the base 61, and fastened thereto by set screws 62. 55 indicates flexible cables for the counterweights. 56 indicates the heel stock being operated upon and, as the operation is the same in both cases, I will now describe the operation briefly.

20 The stock 56 having been placed upon the base, and the hand wheel 11 or 51, as the case may be, having been turned to free the jaws 8 or the springs 30, the pressure head is lowered until the platen 5 or 53 engages the stock 56. Then the hand wheel is operated to drive the screw shaft downward within its collar 9 or 49, and meeting with the resistance of the platen against the stock, it elevates the collar 9 or 49 and operates the toggle arms 7 or 47. Then, in the case of the structure shown in Figs. 1 and 2, the jaws 8 are forced directly against the columns 3, which are supported against the thrust by the link 17, and thereafter the screw forces the platen 5 into compressive operation upon the stock 56. In the case of the structure shown in Figs. 3 and 4, when the toggle 47 begins to operate the cam knuckle 40 turns the cam collar 39 and winds up the spring 30 into binding engagement with the column 31, after which further operation of the screw 50 forces the platen 53 into compressive operation upon the stock 56. In each instance reverse movement of the hand wheel 11 or 51 releases the toggle arms 7 or 47 and the jaws 8 or springs 30, and the pressure head may be readily raised under the balancing action of the counterweights 20.

50 Having described my invention thus fully and suitable means by which the same may

be carried into effect, I wish it understood that I do not limit myself to the specific forms of structure shown and described, nor in general otherwise than as set forth 55 in the claims, read in connection with this specification.

1. A press, comprising a frame including a plurality of standards, a pressure head movable along said standards and having 60 pressure devices movable relatively to said pressure head, and means to secure said pressure head to said standards in adjusted position, said securing means being constructed and arranged to apply a distortive 65 force upon one side of each standard and a countervailing securing force upon the opposite sides of said standards, substantially as described.

2. A heel-press, comprising a frame having standards, a pressure head with a toggle joint pressure device operating upon the standards, and means to countervail the thrust of said toggle against said standards.

3. A heel-press, comprising a frame having standards, a pressure head movable on said standards, and a toggle-joint device to lock said pressure head in adjusted position, including spring construction clamps operated by said toggle devices.

4. A heel-press, comprising frame standards, a pressure head having spring coil locking devices, and a toggle joint operating device to twist said springs and cause the same to clamp said standards throughout 85 the periphery of the latter.

5. A heel-press, comprising frame standards, a pressure head having spring coil locking devices, a toggle joint operating device to twist said springs and cause the same to clamp said standards throughout the periphery of the latter, and cam collars interposed between said toggle and springs to convert the movement of said toggle into rotation to twist said springs.

In testimony whereof I have signed my name to this specification in the presence of two subscribing witnesses.

JOSEPH H. POPE.
